UNITED STATES PATENT OFFICE.

WILLIAM C. JAEGLE, OF NEW YORK, N. Y., ASSIGNOR, BY MESNE ASSIGNMENTS, TO LOUISA OPPERMAN, OF BROOKLYN, NEW YORK.

DEVICE FOR APPLYING AND REMOVING COTTER-PINS.

No. 895,404.

Specification of Letters Patent.

Patented Aug. 4, 1908.

Application filed October 12, 1907. Serial No. 397,046.

To all whom it may concern:

Be it known that I, WILLIAM C. JAEGLE, a citizen of the United States of America, residing in the borough of Manhattan, in the city, county, and State of New York, have invented a Device for Applying and Removing Cotter-Pins, of which the following is a specification.

This invention relates to a device for applying and removing cotter pins, and is particularly applicable for use in situations in which it is difficult, if not impossible, to employ ordinary tools for that purpose.

The objects of my invention are to produce a device, by means of which cotter pins may be introduced in place without destroying their naturally open "set"; another object is to produce a device by means of which the projecting ends of the cotter pin when introduced in place may be opened so as to prevent accidental removal of the cotter pin; another object is to produce a device by means of which the open ends of the cotter pin may be flexed so that the pin can be removed; and another object is to produce a device by means of which the cotter pin may be removed from its seat.

Further objects will appear from an examination of the following specification and accompanying drawings.

In the drawings, Figure 1 is a side elevation of a portion of one embodiment of my invention with the jaws in the separated position. Fig. 2 is a detail view of the same taken at right angles to Fig. 1. Fig. 3 is a detail view of the lower end of the same with the jaws closed. Fig. 4 is an elevation of the extracting device. Fig. 5 is an elevation of a modified embodiment of my invention. Fig. 6 is a detail view taken at right angles thereto. Fig. 7 is a bottom plan view thereof. Fig. 8 is an elevation of a further modification. Fig. 9 is a detail view showing the application of the device for straightening the ends of the cotter pin; and Fig. 10 is a bottom view of the device shown in Fig. 1 showing the cotter pin lying at right angles to that illustrated in Fig. 2.

In all of the views like parts are designated by the same reference characters.

Figs. 1 and 4 represent an embodiment of the invention in which the introducing and extracting mechanism are disconnected. Figs. 5 and 8 show structures in which the applying and extracting mechanism are con-

nected together. In the structure shown in Fig. 1, the device comprises a body 1 of elongated shape having an enlarged head 2 forming a handle. The other end of the body is forked, forming arms 3—3. The body is best formed of steel or other elastic material, and the arms are best formed integral therewith. The free extremities of the arms carry jaws 4—5. The opposing faces of the jaws are set back at an angle, as shown, so that when the two are brought to engagement by flexing the arms 3 they will grip the cotter pin 6 at a point adjacent to the lower faces of the jaws and will bite into the pin and prevent slipping of the pin in the jaws. The arms 3 are normally opened by their elasticity, and are closed by a device sliding upon the body 1 and arms, such device being applicable at a point adjacent to the head 2. This device, as shown in Fig. 1, comprises a rod 7 having extremities bent at an angle with holes through which the body and arms pass, and which slides freely upon such body and arms. The opening of the rod which surrounds the arms is of such a size that when the rod is moved toward the jaws it will inclose and compress the arms together, engaging the jaws and gripping the cotter pin between such jaws. The lower face of the jaw 5 is shown as provided with a recess 8 adapted to engage with the head of the cotter pin 6, to push it home when it has been partly inserted in its seat.

The device for closing the jaws 4 and 5 may be modified, one form being shown in Fig. 5. In this structure, instead of the rod 7, a sleeve 9 surrounding the body and arms is employed. The sleeve is provided with a flange 10, being a means for sliding the sleeve, and for another purpose, which will be described. The lower end of the sleeve fits sufficiently close around the arms 3—3 so that when the sleeve is moved to the position shown in Fig. 5 it will force the two arms together, causing the close engagement of the jaws 4 and 5. In this modification the recess at the bottom of the jaws is formed in both of the jaws instead of in one, the jaws in the modification illustrated in Figs. 5, 6 and 7 being both of the same size. As shown in Fig. 7, the abutting faces of the jaws are provided with notches 11, so that when the jaws engage with the cotter pin the surface engaged with will be greater than if such notches were not used. In Fig. 8 is

shown another modification of means for closing the jaws. In this modification the arms 3-3 are shown as formed integral with the body. One of these arms is made 5 of lighter stock than the other, so that the jaw 5 can be caused to engage with the jaw 4 by pressure exerted upon one side of the arm supporting the jaw 5, the arm supporting the jaw 4 being sufficiently rigid to form 10 a support against which the other jaw engages. Engagement of the two jaws is made by means of a lever 12, which is pivoted to the body and provided with a handle 13 adjacent to that end of the body opposite to 15 the jaws. The other end of the lever 12 is provided with a ring 14, which surrounds the arms 3-3; engagement of the base of the ring with the lighter of the two arms, will, when the lever is caused to pivot, close the 20 two jaws with any degree of pressure desired. The lever 12 may be supported in disengaged position by means of a spring 15, if such is desired.

The device for removing the cotter pin is 25 in the form of a hook 16. This hook may be separate from the body 1, as shown in Figs. 1 and 4, or connected thereto, as shown in Figs. 5 and 8.

In the first embodiment of my invention 30 the device is shown as made in two parts, one part carrying the jaws 4 and 5, and the other part the hook 16. In the other embodiments of my invention, the device is shown as made in one part, such part having the jaws 4 and 35 5 at one end and the hook 16 at the other.

The operation of the embodiment of my invention, described and illustrated, is as follows: To apply the cotter pin it is first placed 40 between the jaws 4 and 5 and the latter closed upon it, as shown in Fig. 2. The engagement of the jaws with the pin should be close to its free ends so that the limbs of the pin may be closed together readily against their normal tendency to remain set in open 45 position. The cotter pin is now introduced into its seat, which may be readily done as the two limbs of the pin are closed. When introduced in its seat, the jaws 4-5 are opened by the reversed movement of the 50 mechanism employed for closing them. The recess 8 on the jaws is then caused to engage with the head of the cotter pin and the latter is pushed home into its seat. If desired the cotter pin may be further secured by sepa- 55 rating its free extremities in the manner shown in Fig. 9, although this will not be necessary ordinarily, as the cotter pin may be introduced by my device without destroying its permanently open "set". To 60 withdraw the cotter pin the hook 16 is used.

If the free ends of the limbs of the cotter pin are widely separated, as shown in Fig. 9, they may be brought together by applying the jaws 4 and 5 to the free end of the limb, 65 as shown in Fig. 9, and swinging the device

so that its longitudinal line is in line with the longitudinal center line of the cotter pin. The free extremities of the cotter pin may then be pinched together by closing the jaws 4-5 upon them with sufficient force to attain this end. In using the structure shown in Fig. 5, the flange 10 may be used as a means for pressing the cotter pin home when it is engaged with the recess 8. Pressure being applied to the flange 10 will always insure that the jaws 4 and 5 will remain in closed position. Fig. 10 illustrates the application of the device to a cotter pin at right angles to the position shown in Fig. 1, which is sometimes desirable in situations where the pin cannot be introduced in line with the tool. The gripping surfaces of the jaws 4 and 5 are set back at an angle, as already described, so that any resistance of the cotter pin to be seated results in a closer grip of the jaws with it.

It is apparent that a device made in accordance with my invention may be used in situations where other tools cannot be employed. This advantage is particularly striking in automobile work in which cotter pins are abundantly used and which are employed in most inaccessible places. If the manipulation shown in Fig. 9 be dispensed with, the cotter pin may be introduced and removed from a place some distance from the seat of the pin, and through a space of relatively small area. The device, therefore, possesses great utility in such situations, as it makes possible the application and removal of cotter pins with the expenditure of a minimum of time, temper and patience.

In accordance with the provisions of the patent statutes, I have described the principle of my invention, together with the apparatus which I now consider to represent the best embodiment thereof, but I desire to have it understood that the apparatus shown is merely illustrative and that the invention can be carried out in other ways.

Having now described my invention, what I claim as new and desire to secure by Letters Patent, is:

1. A device for applying and removing cotter pins, having a body, movable jaws thereon, the opposing faces of the jaws being set back at an angle so that when the two are brought into engagement they will grip the cotter pin at a point adjacent to the lower faces of the jaws, and means for closing the jaws, the said means being operable from the other end of the body.

2. A device for applying and removing cotter pins, having a body, jaws at one end of the body, the opposing faces of the jaws being set back at an angle so that when the two are brought into engagement they will grip the cotter pin at a point adjacent to the lower faces of the jaws, and means operable from the other end of the body for closing

the jaws, and a recessed foot for engagement with the head of the cotter pin.

3. A device for applying and removing cotter pins, having a body, spring arms at one end of the body, jaws upon the spring arms, the opposing faces of the jaws being set back at an angle so that when the two are brought into engagement they will grip the cotter pin at a point adjacent to the lower

faces of the jaws, and a device sliding upon the body for closing the jaws.

This specification signed and witnessed this 10th day of October, 1907.

WILLIAM C. JAEGLE.
